UNITED STATES PATENT OFFICE.

SAMUEL RUTTENBERG AND MEYER F. LEIBOWITZ, OF NEW YORK, N. Y.

CURRENT REGULATOR.

Application filed July 13, 1922. Serial No. 574,805.

To all whom it may concern:

Be it known that we, SAMUEL RUTTENBERG and MEYER F. LEIBOWITZ, citizens of the United States, residents of New York, in the county of New York and State of New York, have invented certain new and useful Improvements in Current Regulators, of which the following is a specification.

This invention relates to improvements in current regulators and is particularly designed for use in connection with what are commonly known in the wireless telegraphy and telephony art as vacuum tubes.

The object of the invention resides in the provision of a device by which the proper quantity of current is passed through the vacuum tube at all times, without the necessity of providing the usual wire-wound rheostat, which while acting satisfactorily in many ways, is liable through missadjustment, to pass too much current and cause the tungsten filament to be burnt out.

Another object of the invention is to provide a device having a novel means for supporting the resistance element, which will hereinafter be termed a filament, in proper position within the capsule forming the body of the regulator.

A further object of the invention is to so prepare the filament as to prevent it from oxidizing and deteriorating.

These and other analogous objects are attained by the novel design, construction and arrangement of parts hereinafter described and shown in the accompanying drawing, forming an essential part of this disclosure, and in which:—

Figure 1 is a plan view of the improved current regulator showing the same mounted and ready for use.

Figure 2 is a side view partly in section of Figure 1.

Figure 3 is a transverse sectional view taken on line 3—3 of Figure 2.

Figure 4 is a detail view of the filament attachment.

Figure 5 is a detail sectional view taken on line 5—5 of Figure 4.

Figure 6 is a longitudinal sectional view through a modified form of the regulator.

Referring to the drawing the numeral 10 designates a base, preferably formed of insulating material, and provided on adjacent opposite ends with binding posts 11,

in electrical contact with which are angularly extending lugs 12.

The capsule is designated generically by the numeral 13 and comprises a tubular body 14 of glass or a similar material, the ends 15 of which are closed to provide a substantially air tight structure.

Lead wires 16, formed of "white" metal or any other suitable conductive substance having approximately the same coefficient of expansion of the material from which the tube 14 is formed, and extending through the end closures 15, sealed and connected to the inner ends of the wire 16, is a filament 17, formed of iron wire or any other suitable material, having a large temperature coefficient of resistance.

As shown in Figures 4 and 5, the ends of the wires 16, are flattened and bent, as at 18, to form a transversely U shaped clamping means which is engaged around the ends of the filament 17, as clearly shown in Figure 5.

Metallic caps 19 are then cemented to the ends of the body 14 and the device mounted, as shown in Figures 1 and 2, and the wires 16 bent around and soldered to the caps 19. The complete cartridge or capsule is then slipped between lugs 12 and held by perforations in the latter.

In the modification illustrated in Figure 6, the tube or capsule is designated by the numeral 20 and the lead wires 21, are sealed in the ends and connected by the filament 22. In this type of device, however, the end caps are eliminated and the device mounted in the circuit in any suitable manner.

A highly important feature in the production of such a device is to so prepare the filament as to prevent oxidization and to accomplish this result, the iron filament prior to being introduced into the capsule, is preferably dipped in a mixture of alcohol and phosphorus. Any other suitable method or material may be employed which will produce the desired results. After introduction into the capsule the device is connected so that an initial current is passed through the filament and its temperature raised to approximately 500 degrees C. This action causes the phosphorus to unite with the oxygen in the tube, thus preventing the filament from oxidization when in use.

It has also been found that the oxygen

in the capsule can be absorbed by putting a small amount of the phosphorus mixture inside the tube before sealing. The heat of the glass during sealing will heat the phosphorus to the desired temperature.

By providing an alkaline coating on the filament deterioration of the latter will be prevented.

While certain preferred embodiments of this device have been shown and described, it will be understood that changes in the form, arrangements, proportions, sizes and details thereof, may be made without departing from the scope of the invention as defined in the appended claims.

Having thus described our invention, what we claim as new and desire to secure by Letters Patent, is:—

1. A device in cartridge form for automatic regulation of the current in an audion tube filament.

2. A current regulator in cartridge form for vacuum tubes comprising a capsule, lead wires extending through opposite ends of the capsule, a filament clamped to the inner ends of the lead wires, and a coating applied to the filament prior to its introduction into the capsule when the temperature of the filament is raised within certain limits.

3. A current regulator in cartridge form for vacuum tubes comprising a capsule, lead wires extending through opposite ends of the capsule, a filament connecting the inner ends of the lead wires and means associated with the filament for reducing the oxygen content of the capsule when the temperature of the filament is raised to a predetermined degree.

4. A current regulator in cartridge form for vacuum tubes comprising a capsule, lead

wires extending through opposite ends of the capsule, a filament clamped to the inner ends of the lead wires, and a coating applied to the filament prior to its introduction into the capsule for reducing the oxygen content of the capsule when the temperature of the filament is raised with certain limits.

5. A current regulator in cartridge form for vacuum tubes comprising a capsule, lead wires extending through opposite ends of the capsule, a filament connecting the inner ends of the lead wires, means associated with the filament for reducing the oxygen content of the capsule when the temperature of the filament is raised to a predetermined degree, and an alkaline coating for the filament to prevent corrosion.

6. A current regulator in cartridge form for vacuum tubes comprising a capsule, lead wires extending through opposite ends of the capsule, a filament connecting the inner ends of the lead wires, and a phosphoretic coating on said filament for reducing the oxygen content of the capsule when said filament is raised in temperature.

7. A current regulator in cartridge form for vacuum tubes comprising a capsule, lead wires extending through opposite ends of the capsule, said lead wires having spatulate inner ends bent to produce opposed clamping surfaces, a filament engaged between the clamping surfaces in electrical contact therewith, and a protective coating applied to said filament.

Signed at New York in the county of New York and State of New York this 26th day of May, A. D. 1922.

MEYER F. LEIBOWITZ.
SAMUEL RUTTENBERG.
